UNITED STATES PATENT OFFICE.

E. FORREST WEAVER, OF PHILADELPHIA, PENNSYLVANIA, ASSIGNOR OF
ONE-HALF TO GEORGE H. PERKINS, OF SAME PLACE.

REVOLVING TELEPHONE-STAND.

SPECIFICATION forming part of Letters Patent No. 317,252, dated May 5, 1885.

Application filed October 11, 1884. (No model.)

To all whom it may concern:

Be it known that I, E. FORREST WEAVER, a citizen of the United States, residing in the city and county of Philadelphia, in the State 5 of Pennsylvania, have invented certain Improvements in Revolving Telephone-Stands, of which the following is a specification.

The principal object of this invention is the improvement of a certain revolving telephone-stand invented by me and patented to me under date of June 28, 1881, in and by United States Letters Patent No. 243,663; but its further object is the provision of an accurately-operating mechanism by the use of which any 15 device dependent for its operation upon the continuous transmission of an electric current or currents, and which is at the same time intended to be revolved about a fixed pivot, can be accurately revolved without disarrangement of its wires or conductors or dis-establishment of its electric current. My improved device, in other words, is such as to insure the continuous electrical connection of a series of divided wires for the uninterrupted 20 passage of an electric current at whatever position in its path a revoluble device connected with said wires, be it an electric transmitter, an electric flash or signal light, or other contrivance, may be placed.

Reference to the Letters Patent above mentioned will show that the contrivances therein set forth consist, essentially, of a revoluble wire-holder, upon a lateral extension of which a telephone-transmitter or kindred electric 35 device is mounted, a fixed standard, within which said holder is erected and revolved, what is termed an "upper disk," connected and adapted to revolve with the wire-holder, and a fixed disk adjusted to make contact 40 with the upper disk, and conveniently applied below the table or surface upon which the standard was mounted.

In the said patented device the opposing faces of the disks are respectively provided 45 with corresponding opposite series of suitably-insulated concentric rings, in which rings the wires of the different circuits are respectively entered, so that although the wires themselves are divided at the disks, yet by virtue 50 of their being embedded in the conducting-rings of the respective disks, which by op-

posite pairs are in contact, a given circuit is established through a given divided wire by the interposition of said conducting-rings, and the connection is complete so long as the rings 55 are in contact, whatever may be the relative position of the revoluble disk and its connected appliances with respect to the fixed disk. Transmission of current is of course dependent upon the contact of opposing pairs 60 of conducting-rings. A complete understanding of my former invention can be had by a reference to the patent above mentioned.

In the operation of my above-mentioned device it has been found that after long use the 65 conducting-rings of the disks tend to wear away in such manner that adjustment of the disks or replacement of the rings becomes necessary. The specific object of my present invention is to so improve upon the aforesaid 70 disks as to render them more durable, and thereby save the expense of repairs and adjustment. These results I accomplish by mechanism a preferred form of a convenient embodiment of which is represented in the accompanying drawings, and described in the 75 following specification, the particular matter claimed as novel being hereinafter definitely specified.

In the accompanying drawings, Figure 1 is 80 a central vertical partially-sectional side elevation of a revolving telephone-stand conveniently embodying my improvements. Fig. 2 is a central vertical sectional enlarged elevation through the base of the standard, representing the disks or supporting-plates which carry, respectively, the concentric conducting-rings and the spring-controlled knobs or buttons. Fig. 3 is a central vertical magnified elevational detail through one of the 85 spring-controlled brushes, knobs, or buttons and a part of its ring. Fig. 4 is a top plan view of the fixed or under disk, and Fig. 5 is an under plan view of the movable disk which is provided with the series of concentric rings. 90

Similar letters of reference indicate corresponding parts in all the figures.

In the accompanying drawings, A represents a portion of a stand, table, or operator's desk.

B is a vertical standard, of any convenient construction, made hollow to contain a tube

or other wire-holding revoluble stem, C, which, if desired, above the standard branches at an angle, and is provided with a telephonic transmitter, signal-light, or other electrical device, 5 D. The wire-holder C contains or carries the upper wires, E, which form portions of circuits, the other portions of which are completed in the devices carried by the disks and in the lower wires, E', which are represented as passing out below the table. The revoluble wire-holding tube C is provided with a disk or other supporting-plate, F, called herein the "upper disk," which is provided with a series of concentric rings, f, of conducting material, suitably insulated from each other. Into each of these rings one extremity of one of the upper wires E is shown embedded. The upper disk, as already stated, revolves with the wire-holder and its supported device to be revolved. 10 G is the fixed or lower disk or kindred supporting-plate, best made of insulating material, and conveniently supported upon a multi-armed or other suitable spring, H, secured upon the table or other fixed support. The fixed disk is best of the same diameter as that of the revoluble disk, and it is provided as to its upper face with a series of cells, g, or sockets, preferably of conducting material, which 15 are respectively placed at radial distances upon the fixed disk corresponding to the radial distance of a given ring upon the upper disk from the center of said disk. The cells are preferably hollow cylinders closed at their base, and contain a spiral or other suitable spring, g', upon which is superimposed a knob or button, g'', of conducting material. The free extremities of the lower wires are respectively led up through a hole, a, in the table through a central aperture, f'', in the lower disk, and are thence conducted conveniently through channels f', formed for the purpose radially outward, and are connected or respectively entered into the closed bases 20 of the cells. The proportions and strength of the springs in the cells are such as to cause the knobs or buttons to project a given distance above the upper face of the lower disk. The number of cells and knobs or buttons 25 tons is correspondent to the number of rings, and the cells are, as stated, set at different radial distances corresponding to the position of the rings in the upper disk, so that each knob or button makes contact with a given ring, and in the revolution of the rings with the upper disk remains in contact with its ring under the stress of its spiral spring. The accurate support of the lower disk in a plane parallel with the plane of the face of 30 the upper disk is conveniently secured by the support of the lower disk upon the multi-armed spring, and it is obvious that the said supporting spring or cushion co-operates with the cell-springs in securing the continual and 35 certain contact of the knobs or buttons with their respective rings. The circuits are completed through given upper wires, given lower

wires, given rings, and given knobs, cells, and springs.

The precise mechanical arrangement described is not an essential of the invention, as it is obvious that if the cells were of non-conducting material, and the lower wires entered through them, so as to make contact with the spiral springs, the electrical connection would 75 be complete.

The construction of the upper disk need not necessarily be that represented in the drawings, although the latter is a convenient construction. Any given number of rings 80 may be employed, and a corresponding number of knobs or buttons be applied to the lower disk. I have represented the disks as inclosed in a chamber formed in the base of the standard. It is obvious, however, that 85 they need not be inclosed, and that they may be otherwise located than within the standard.

It will be readily understood that in the operation of my device contact through the 90 different circuits is insured, whatever may be the position of the revoluble wire-tube with respect to its path of movement.

This contrivance obviates the necessity of all adjustment of the lower disk, and secures 95 the constant and accurate contact of the respective knobs or buttons with their respective rings.

It is obvious that, if desired, the rings may be applied to the lower disk and the spring-controlled knobs or buttons to the upper. That arrangement which I have represented is, however, that which I prefer. It is obvious, also, that while disks are the most convenient plates or supporting devices for containing the 100 rings and the knobs or buttons, yet that other supporting contrivances may be substituted in the stead of disks. It is obvious, again, that the wire-holder or containing-tube is in itself simply a revoluble standard whose office is 105 that of supporting the revoluble transmitter or device to be revolved and the disk or plate which carries the concentric rings, and of containing the upper portions of the divided wires. It need not necessarily be a tube, although the tube is the best form of which I 110 have present knowledge. The cells also are simply cages or containing devices for the knobs or buttons.

Having thus described my invention, I claim 115 and desire to secure by Letters Patent—

1. In combination with the wires of a given electric circuit, which are divided at a given point, a series of concentric insulated conducting-rings, with which portions of the divided 125 wires are connected, and a series of spring-controlled knobs or buttons, which make contact, respectively, with and are adapted to be rotated against the rings, and with which the other portions of the divided wires are connected, substantially as set forth.

2. In combination with the wires of a telephone-transmitter, signal-light, or other electric device, which are divided at a given point,

a pair of disks or supporting-plates of insulating material, respectively provided with a series of concentric conducting-rings and a series of spring-controlled knobs or buttons, 5 with which rings and knobs, respectively, the divided wires are connected, substantially in the manner and for the purpose specified.

3. In combination with a telephone-transmitter or other electrical device so supported 10 as to be capable of a revolution about a fixed point, a revoluble tube or holder for supporting said transmitter and for containing a series of wires, a series of concentric conducting-rings, a disk or plate carried by the tube and 15 adapted to revolve with said tube for supporting said rings, a series of spring-controlled knobs or buttons corresponding in number to the rings aforesaid and respectively making contact with the said rings, and a disk or plate 20 for supporting said spring-controlled buttons, substantially as set forth.

4. In combination with a telephone-transmitter or other electrical device so supported as to be capable of a revolution about a fixed 25 point, a revoluble tube or holder for supporting said transmitter and for containing a series of wires, a series of concentric conducting-rings mounted upon a disk or plate carried by the tube and adapted to revolve with 30 said tube, a series of spring-controlled knobs or buttons corresponding in number to the rings aforesaid, respectively making contact with the said rings, and mounted upon a disk

or plate for supporting said spring-controlled buttons, and a spring-support for retaining 35 the button-carrying plate in position against the ring-carrying plate, substantially as described.

5. In combination with a revoluble disk or plate provided with a series of suitably-insulated conducting-rings, a fixed disk or plate provided with a series of cells containing spring-controlled knobs or buttons, and respectively disposed at such radial distance 40 from the center of said fixed disk as to cause 45 the knobs or buttons to make contact, respectively, with different conducting-rings, substantially as set forth.

6. In combination with a series of concentric suitably-insulated conducting-rings, a series 50 of spring-controlled knobs or buttons respectively disposed to make contact with and to be rotated against different rings, divided wires of the same circuits respectively as to their divided extremities electrically connected with the rings and the knobs or buttons aforesaid, and disks, plates, or kindred devices for retaining the rings and knobs or buttons in contact, substantially as set forth.

In testimony whereof I have hereunto signed 60 my name this 8th day of October, A. D. 1884.

E. FORREST WEAVER.

In presence of—

J. BONSALL TAYLOR,
W. C. STRAWBRIDGE.
